UNITED STATES PATENT OFFICE

2,165,895

HOISTING MECHANISM

Joseph F. Joy, Claremont, N. H., assignor to Sullivan Machinery Company, a corporation of Massachusetts

Original application July 1, 1935, Serial No. 29,308. Divided and this application March 19, 1936, Serial No. 69,696

8 Claims. (Cl. 254—166)

This invention relates to hoisting mechanisms, and more particularly to improvements in hoisting mechanisms of the portable tractor mounted type.

5 An object of this invention is to provide an improved portable hoisting mechanism. Another object is to provide an improved portable hoisting mechanism of the self-propelled type whereby the hoist may be maneuvered with facility into different operating positions and may be readily transported by its own self-propelling mechanism from one working place to another. A further object is to provide an improved hoisting mechanism having a novel arrangement of 10 the hoisting drums and improved driving and controlling means for the drums. A still further object is to provide an improved hoisting mechanism of the tractor tread supported and propelled type. These and other objects and advantages of the invention will, however, hereinafter more fully appear.

This application is a division of my copending application Ser. No. 29,308, filed July 1, 1935, and patented April 12, 1938, No. 2,113,760.

25 In the accompanying drawings there is shown for purposes of illustration one form which the invention may assume in practice.

In these drawings:

Fig. 1 is a plan view of the illustrative form of 30 the improved self-propelled hoisting mechanism.

Fig. 2 is a side elevational view of the hoisting mechanism shown in Fig. 1, with a portion of the casing broken away to illustrate details of the interior construction.

35 Fig. 3 is an enlarged view in longitudinal section taken substantially on line 3—3 of Fig. 1.

Fig. 4 is a cross sectional view taken substantially on line 4—4 of Fig. 3.

Fig. 5 is a horizontal sectional view taken substantially on line 5—5 of Fig. 3.

Fig. 6 is an enlarged vertical sectional view illustrating the drum clutch control mechanism shown in Fig. 3, the view taken substantially on line 6—6 of Fig. 5.

45 Fig. 7 is a horizontal sectional view taken substantially on line 7—7 of Fig. 3.

Fig. 8 is a diagrammatic view showing the improved hydraulic fluid system and the associated control means.

50 Fig. 9 is a detail sectional view illustrating the by-pass valve.

In this illustrative embodiment there is shown a hoisting mechanism generally designated 1 of the tractor mounted, self-propelled type, especially designed for use in drag scraper work,

generally comprising a self-propelled base 3 having mounted thereon hoisting drum means generally designated 4. The base 3 comprises a body 5 mounted on and supported by endless track-laying treads 6, 6 arranged at opposite sides of the body. The tractor treads comprise tread frames 7 rigidly secured to the sides of the body 5 and embodying upper and lower guide members 8 and 9 having guideways in which are guided endless track-laying chains 10. These track-laying chains are herein of the block type carrying cleat-like plates engageable with the mine floor for propelling the hoist. The forward portions of these endless tractor chains are guided by guide sprockets 11 journaled on adjustable bearing blocks 12 mounted in longitudinal guideways 13 formed on the tread side frames 7, and these bearing blocks are adjustable longitudinally within their guideways by means of adjusting screws 14. By adjusting the screws 14 the bearing blocks 12 may be slid in their guideways to move the guide sprockets 11 longitudinally with respect to the tread frames 7, thereby to take up any undue slack in the chains. The rearward portions of the tread chains engage drive sprockets 15, 15 having their hubs keyed to the projecting ends of aligned rear axles 16 and 17 journaled in bearings 18 supported by bearing supports 19 attached to a differential housing 20 secured to the hoist body 5. Arranged within this differential housing is a differential 21 of a standard automotive design including a rotatable support 22 carrying bevel planet gears 23 meshing with coaxial bevel gears 24 and 25 fixed to the aligned axles 16 and 17, respectively, and the support 22 is driven by a worm wheel 26 fixed thereto and meshing with the teeth of a drive worm 27. As shown in Fig. 3, the drive worm 27 is fixed to a longitudinal shaft 28 journaled within bearings 29 supported within the differential housing 20. Arranged centrally within the hoist body 5 is a motor 30, herein preferably of the reversible electric type, having its power shaft 31 horizontally disposed and extending longitudinally of the hoist body. Connected to the rear end of the motor power shaft by a coupling 32 of a conventional design is a planetary, slip controlled change speed mechanism generally designated 33, likewise of a standard automotive design, and embodying frictionally controlled planet gears for effecting drive of a shaft 34 at high, low and medium speeds, under frictional control at each speed, and also reverse frictionally controlled drive of the shaft 34. As this planetary transmission mechanism is of a

well known design, detailed description thereof is herein considered unnecessary. Connectible to the shaft 34 by a clutch 35 is an alined shaft 36 suitably journaled within the hoist body and having keyed thereto a spur pinion 37 meshing with a spur gear 38 keyed to the longitudinal worm drive shaft 28 heretofore referred to. As shown in Fig. 4, fixed to the inner sides of the tread chain drive sprockets 15, 15 are brake drums 39 and 40, respectively, having cooperating therewith contractable brake bands 41 and 42. Each of these brake bands is provided with a suitable lever type operating mechanism 43 controlled by a hand lever 44. From the foregoing it will be evident that the track-laying treads may be driven by the motor 30 under frictional control at three forward speeds and in reverse by the planetary transmission mechanism 33, clutch 35, shaft 36, spur gearing 37, 38, worm gearing 27, 28, differential gears 23, 24, 25 and the alined axles 16 and 17 driving the sprockets 15, 15. By regulating the brake bands 41 and 42 the drive of the track-laying treads may be controlled to effect speeding up of the drive of one tread and slowing down of the other, thereby to enable steering of the hoist as it is propelled over the mine floor in a well known manner. It will thus be seen that the hoist is self-propelled and may be moved and guided by the track-laying treads during propulsion thereof over the mine floor.

The hoisting means generally designated 4 embodies a pair of relatively rotatable hoisting or haulage drums 48 and 49 arranged in superimposed coaxial relation on the upper portion of the hoist body, and wound on these drums are portions 50 and 51 of an endless drag line or haulage cable or rope, as shown in Fig. 2. These drums are journaled for rotation about a vertical axis on bearings supported by a centrally located tubular shaft 52 in turn journaled in bearings supported within a front gear housing 53 attached to the front end of the hoist body 5. Disc clutches 54, 55 are provided for connecting the drums 48 and 49 to the tubular shaft 52. Keyed to the forward end of the motor power shaft 31 is a spur pinion 56 meshing, as shown most clearly in Fig. 5, with a spur gear 57 keyed to a longitudinal shaft 58 suitably journaled in the gearing housing 53. Fixed to this shaft is a worm 59 meshing with a horizontal worm wheel 60 arranged within the gearing housing and fixed to the lower end of the vertical shaft 52 (see also Fig. 6).

55 The operating means for the disc clutches 54 and 55 comprises, as shown most clearly in Fig. 6, a servo-motor having a hydraulic cylinder 61 arranged coaxially with and projecting within the tubular shaft 52 (see also Fig. 3). This cylinder contains a vertically reciprocable piston 62 having fixed thereto a tubular rod 63 projecting upwardly through the packed upper head 64 of the cylinder and threadedly secured at its upper end within a block 65 above the upper hoisting drum. Also fixed within the piston 62 and extending coaxially through the tubular rod 63 is a tubular rod 66 having its upper end threadedly fixed within an upper block 67. The block 67 has a depending cylindrical projection 68 which fits tightly in a bore formed in the lower block 65, thereby to provide an upper closure for a chamber 69 in the lower block. Formed in the upper block is a chamber 70 with which the inner tubular rod 66 communicates. Hydraulic pressure is adapted to be supplied to

the chambers 68 and 70 in the blocks in a manner to be later described. The clutches 54, 55 are provided with a clutch applying plate 71 having engaging its opposite surfaces ball thrust bearings 72, 73, and surrounding the tubular 5 rod 63 is a tubular sleeve 74, while engaging the lower thrust bearing 73 and fixed to the tubular rod 63 is a collar 75. The sleeve 74 is guided in a bore 76 formed in a top cap plate 77 threadedly secured within the upper end of the tubular 10 shaft 52 and forming a housing for the upper bearing of the hoisting drum 48. The shaft 52 is vertically slotted at 78 and the arms of the clutch applying plate 71 project through these slots into engagement with the thrust bearings 15 72, 73 in the manner shown. When hydraulic pressure is supplied from the chamber 70 through the inner tubular rod 66 and through an axial opening 79 in the piston to the lower end of the hydraulic cylinder, the piston 62 is moved upwardly to shift the clutch applying plate 71 in a direction to apply the upper clutch 54 to connect the upper drum 48 to the drive shaft 52. When hydraulic pressure is supplied from the chamber 69 through the tubular rod 63 and 20 openings 80 in the lower end of the rod to the upper end of the hydraulic cylinder, the piston 62 is moved downwardly to move the clutch applying plate 71 in a direction to apply the lower clutch 55 to connect the lower drum 49 to the 25 drive shaft 52. It is accordingly evident that the hoisting drums 48 and 49 may be selectively connected in driving relation with the motor 30 and are driven from the motor through the spur gearing 56, 57, worm gearing 59, 60 and the vertical drive shaft 52.

In this illustrative construction, mounted within the rearward portion of the hoist body 5 is a controller and resistance box 85 connected by an electrical conductor cable 86 to a switch 40 and fuse box 87, and an electrical conductor cable 88 to the motor 30. Arranged at opposite sides of the hoist body and rigidly fixed within the side tread frames between the latter and the differential housing is a pair of hydraulic anchor 45 jacks 89 each comprising a vertical hydraulic cylinder 90 containing a vertically reciprocable piston 91 having an upwardly extending piston rod 92 passing through a packed opening in the upper cylinder head 93. The upper end of the piston rods 92 are provided with abutment 50 engaging points 94 for engagement with a suitable extraneous abutment, for instance the mine roof, for rigidly jacking the hoist in a stationary operating position against the mine floor.

The means for supplying hydraulic pressure to the jack cylinders 90 and the operating cylinder 61 for the drum control clutches comprises a hydraulic pump 96, preferably of a conventional triple rotor type, attached to the gear housing 60 53 and having a pump chamber 97 containing intermeshing pump rotor gears 98, one of which is keyed to the projecting end of the longitudinal drive shaft 58, as shown in Fig. 5. The chamber within the gear housing 53 provides a reservoir 99 for containing a liquid, and this pump is adapted to pump liquid under pressure from the reservoir through suitable passages and conduits, to be later described, to the hydraulic cylinders above referred to. Now referring to the 70 hydraulic fluid system and the associated control means shown in Figs. 8 and 9, it will be observed that the discharge chambers of the rotors of the pump 96 are connected through conduits 100 and 101 respectively, to a by-pass valve device 102, 75

and a return conduit 103 connects the by-pass valve device to the reservoir 99. The main supply conduit 104 leads from the by-pass valve device to a control valve box 105. As shown in Fig. 9, the by-pass valve device 102 comprises a valve box 106 having a passage 107 connecting the conduit 100 to the conduit 104. A parallel passage 108 communicates with the conduit 101 and is connected by a passage 109 to the passage 107. Formed in the valve box is a chamber 110 communicating with the conduit 103 and connected by a passage 111 to the passage 108. The passages 109 and 111 are controlled by end seating valves 112 and 113 respectively, having a pivoted control lever 114. When the valves 112, 113 are in the position shown in Fig. 9, passages 107, 108 are connected together by the passage 109 so that both conduits 100 and 101 communicate with the conduit 104. When the control lever 114 is swung into its opposite position, the passage 109 is closed by the valve 112, while the passage 111 is open so that the conduit 101 communicates with the return conduit 103 through passage 111 and chamber 110 and the conduit 108 communicates through the passage 107 with the conduit 104. Again referring to Fig. 8, it will be noted that the control valve box 105 has parallel vertical bores 115 containing rotary control valves 116 and 117 respectively, each having a manual control handle. The lower ends of the valve bores are connected by a supply passage 118 with which the supply conduit 104 communicates, while a discharge passage 119 connects the upper ends of the valve bores with a return conduit 120 leading to the reservoir 99. The valve 116 controls the supply of liquid pressure to the clutch control cylinder 61 and conduits 120, 121 connect the chambers 70, 69 in the block 67, 65, respectively, (see also Fig. 6) with the bore of the valve 116. The valve 117 controls the supply of liquid pressure to the anchor jack cylinders, and the valve bore is connected by a conduit 122 and branch conduits 123 to the upper ends of the anchor jack cylinders, while the valve bore is connected through a conduit 124 and branch passages 125 to the lower ends of the anchor jack cylinders. When the valve 116 is in the position shown in Fig. 8, liquid under pressure may flow from the supply passage 118 through a passage on the valve 116, conduit 120, chamber 70, tubular rod 68 and passage 79 in the piston 62 to the lower end of the clutch control cylinder 61, thereby to effect upward movement of the piston 62 to apply the friction clutch 54 for the upper hoist drum 48, while the upper end of the cylinder 61 is connected to exhaust through passages 80, tubular rod 63, chamber 69, conduit 121 and a passage on the valve 116 communicating with the discharge passage 119. When the position of the valve 116 is reversed, liquid under pressure may flow from the supply passage 118 through a passage on the valve 116, conduit 121, chamber 69, tubular rod 63 and passages 80 to the upper end of the hydraulic cylinder 61 to effect downward movement of the piston 62 to apply the friction clutch 55 for the lower hoist drum 49, while the lower end of the cylinder 61 is connected through passage 79, tubular rod 66, chamber 70, conduit 120 and a passage on the valve 116 to the discharge passage 119. When the valve 117 is in the position shown in Fig. 8, liquid under pressure may flow from the supply passage 118 through a passage on the valve 117, conduit 124 and branch conduits 125 to the lower ends of the anchor jack cylinders to effect upward movement of the an-

chor jack pistons in an anchoring position, while the upper ends of the anchor jack cylinders are connected through the branch conduits 123, conduit 122 and a passage on the valve to the discharge passage 119. When the position of the valve 117 is reversed, liquid under pressure may flow from the supply passage 118 through a passage on the valve, conduit 122 and branch conduits 123 to the upper ends of the jack cylinders to effect downward movement of the anchor jack pistons into their released position, while the lower ends of the jack cylinders are connected through branch conduits 125, conduit 124, a passage on the valve 117 to the discharge passage 119. When the valves 116, 117 are moved into their closed position, the liquid is trapped in the cylinders, and when liquid flow through the supply conduit 104 is cut off by the valves 116, 117, the liquid discharged from the pump is by-passed through the by-pass valve device back to the reservoir 99. When both conduits 100 and 101 are connected with the conduit 104, the pressure in the hydraulic system is, of course, increased, since liquid is pumped at that time from both discharge chambers of the pump.

The general mode of use of the improved hoisting mechanism will be clearly apparent from the description given. The hoisting mechanism is propelled about the mine over the mine floor by the endless track-laying treads under the control of the frictionally controlled planet gears of the change speed mechanism at the desired speed. When the working place is reached, the hoisting mechanism is rigidly jacked in a stationary operating position against the mine floor by means of the hydraulic anchor jacks engaging an extraneous abutment such as the mine roof. The hoisting cables 50 and 51 are then extended from the hoisting drums 48 and 49 to the drag scraper mechanism to be moved thereby, and one or the other of the friction clutches 54, 55 is applied to cause one cable to be wound in by its drum while the other cable is paid out by its drum. Other uses and advantages of the improved hoisting mechanism will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a hoisting mechanism, a base, relatively rotatable hoisting drums mounted on said base, a motor on said base, means driven by said motor for driving said drums, a hydraulic pump driven by said motor, and hydraulic means operated by pressure fluid discharged from said pump for controlling the connection of said drums with said drum driving means.

2. In a hoisting mechanism, a base, relatively rotatable hoisting drums arranged in superimposed coaxial relation on said base, a motor on said base, means driven by said motor for driving said drums, a hydraulic pump driven by said motor, and hydraulically operated means operated by pressure fluid discharged from said pump for controlling the connection of said drums with said drum driving means.

3. In a hoisting mechanism, relatively rotatable cable winding drums, a tubular drive shaft

- 5 coaxial therewith, clutches for selectively connecting said drums in driving relation with said tubular drive shaft for driving by the latter, and means for operating said clutches including clutch operating connections arranged coaxially with said tubular drive shaft, and motor means arranged at least in part within said tubular shaft for actuating said coaxial clutch operating connections.
- 10 4. In a hoisting mechanism, relatively rotatable cable winding drums, a tubular drive shaft coaxial therewith, friction clutches for selectively connecting said drums in driving relation with said tubular drive shaft, and hydraulically operated means for operating said clutches including a cylinder arranged coaxially with said tubular drive shaft and arranged at least in part within the latter, and a clutch operating piston reciprocable within said cylinder.
- 15 5. In a hoisting mechanism, relatively rotatable cable winding drums, a tubular drive shaft coaxial therewith, clutches for selectively connecting said drums in driving relation with said tubular drive shaft, hydraulically operated means for operating said clutches including a cylinder arranged coaxially with said tubular drive shaft at one end of the latter and a clutch operating piston reciprocable within said cylinder, and a connection at the opposite end of said shaft for conducting hydraulic pressure from a source of pressure supply to said cylinder.
- 20 6. In a hoisting mechanism, relatively rotatable cable winding drums, a tubular drive shaft coaxial therewith, clutches for selectively connecting said drums in driving relation with said tubular drive shaft, hydraulically operated means including a cylinder arranged coaxially with said tubular drive shaft at one end of the latter and a piston reciprocable within said cylinder and having a piston rod extending cen-
- 5 trally within said shaft for operating said clutches, and a connection at the opposite end of said shaft for supplying hydraulic pressure to said cylinder and including passage means formed in said piston rod.
- 10 7. In a hoisting mechanism, a frame having a horizontal top surface, a drive shaft arranged on a vertical axis and journaled in said frame, the upper end portion of said shaft projecting above the top surface of said frame, a pair of 15 relatively rotatable cable winding hoisting drums arranged in superimposed coaxial relation above the top surface of said frame, said drums having hoisting cables respectively wound thereon, said drums surrounding and journaled on the upwardly projecting portion of said shaft, a driving gear arranged within said frame for driving said shaft, friction clutches arranged within said drums and operable at will for connecting said drums to said shaft for driving thereby.
- 20 8. In a hoisting mechanism, a portable base having traction means, the forward portion of said base projecting horizontally in advance of said traction means, a pair of relatively rotatable cable winding hoisting drums arranged in superimposed coaxial abutting relation on the top of said forwardly projecting base portion, said drums having hoisting cables respectively wound thereon, a motor on said base, means driven by said motor for driving said drums including a vertical drive shaft journaled within said projecting base portion and having a portion projecting upwardly above the top of said projecting base portion, bearing means for journaling said drums on said projecting shaft portion, and friction clutches within said drums and operable at will for only alternately connecting the latter to said shaft for driving thereby.

JOSEPH F. JOY. 40
